UNITED STATES PATENT OFFICE.

ROGER S. WHITE, OF WASHINGTON, DISTRICT OF COLUMBIA.

ELECTRIC SWITCH.

1,228,858.

Specification of Letters Patent.

Patented June 5, 1917.

Application filed October 31, 1914. Serial No. 869,598.

To all whom it may concern:

Be it known that I, ROGER S. WHITE, a citizen of the United States, residing at Washington, in the District of Columbia, 5 have invented certain new and useful Improvements in Electric Switches, of which the following is a specification.

This invention relates to improvements in switching or connecting devices for electric circuits. In electric meter test blocks, for which my invention is especially suited, a number of terminals and connecting devices are usually exposed in a comparatively restricted space, and in making the changes 10 in the circuits required for connecting in the test meter and then restoring the normal connections of the wires after the meter has been tested, there is always danger of shock to the operator in handling the connections, and also danger of short circuits 15 from detachable or movable connecting devices being dropped upon or accidentally moved against live terminals. Usually, also, with the methods now employed in making 20 meter tests, more of the operator's time is required in making the necessary circuit changes than for making the meter tests.

One purpose of my invention is to provide a compact switching mechanism which 30 may be assembled upon a meter test block and manipulated to make the necessary changes in the circuits with a minimum liability to shocks or short circuits, and with a great saving in time over present 35 methods. As very little space is required for operating the switches of my invention to open and close the circuits, the test block, with its terminals and switches, may be made small enough to be placed within the 40 meter casing instead of being arranged outside of the casing on the wall, or in a separate box, as is customary. While the invention is applicable particularly to meter test blocks, it is also suitable for many 45 other purposes, where connections are to be made or broken between dead terminals, or terminals between which there is only a slight difference of potential.

In the accompanying drawing, which 50 illustrates my invention,

Figure 1 is a central section through a switching device of my invention, showing the same applied to a panel of insulating

material, the terminals for the wires being arranged at one side of the panel and the connecting member at the opposite side;

Fig. 2 is a front view of a portion of the panel, showing two of the switching devices in end view, and a jumper connecting the same;

Fig. 3 is a central sectional view through another form of switching device embodying my invention, mounted upon a panel, the connecting member being at one side of the panel and the wire terminals at the 60 opposite side;

Fig. 4 is a front elevation of the connecting plate shown in Fig. 3;

Fig. 5 is a central sectional view through a switching device applied to two conducting strips arranged upon the same side of a panel as the connecting device; and

Fig. 6 is a front view of the conducting strips and connection shown in Fig. 5.

Referring to Figs. 1 and 2 of the drawing, 75 1 represents a slab of insulating material, such as a switchboard panel or the base of a meter test block, and 2 indicates an opening bored through the slab for the purpose of permitting one of the connecting devices to 80 extend through from one side of the board or slab to the other. As shown, the connecting device comprises a metal bolt 3, threaded at both ends, a surrounding metal tube 4, shorter than the bolt, and insulated therefrom by a tube of insulating material 5, the tube 4 being provided at one end with a metal head 6, which is preferably threaded on to the tube, and the stud or bolt 3 being provided with a threaded metal nut or cap 90 7, which is adjustable on the stud into and out of engagement with the head 6 on the tube. A wire terminal 8 is electrically and mechanically connected to the stud 3 by clamping nuts 9, on the stud, and another 95 wire terminal 10 is electrically and mechanically connected to the surrounding tube 4 by clamping nuts 11. The conducting tube 4 and the insulating tube 5 are held in fixed positions upon the stud 3, between 100 a clamping nut 12, of insulating material, upon the end 3^a of the stud and a nut or washer 13, also of insulating material, arranged upon the end 3^b of the stud between the tubes and one of the clamping nuts 9. 105 The cap 7 is hollowed out, as shown at 7^a,

so that it may extend over and around the clamping nut 12 and engage the head 6 on the tube 4. The clamping nut 12 is also of slightly smaller diameter than the tube 4 so that the head 6 may be placed upon or taken off of the tube without disturbing the nut 12 which clamps the tubes 4 and 5 to the stud.

It will be seen that in order to attach the device to a switch, the terminals 8 and 10 being connected to the stud and conducting tube respectively, it is only necessary to pass the tube through the opening in the board and apply the head 6, which holds the entire device in place. The cap 7 is then applied to the stud and the adjustment of this cap into and out of engagement with the head 6 connects or disconnects the bolt with the tube, and hence connects or disconnects the terminal 8 with the terminal 10. The terminals, it will be seen, are at one side of the panel 1, while the adjustable connecting cap 7 is at the opposite side of the panel. It will be evident that where the wires and their connecting terminals are concealed, either in a casing or at the back of a switch-board, the devices described form a convenient means of connecting and disconnecting the terminals from the outer side of the casing or the front of the board. In Fig. 2, a portion of the front of a board, or the outer wall of a casing, is shown equipped with two of my connecting devices, *a* and *b*, for the purpose of illustration. It will be noted in Fig. 1 that the head 6 is provided with a groove 6^a, and in Fig. 2, a jumper wire 14 is shown sprung into the grooves on the members 6 of adjacent switching devices, this being a convenient way of bridging such adjacent devices, for meter testing, where the devices are applied to meter test blocks.

In Fig. 3, the wire terminals 8^a and 10^a are also at one side of the panel 1, while the cap 7 which makes the electrical connection between these terminals is at the opposite side of the panel. In the form of the invention shown in this view, the stud 3^a, upon which the cap 7 is mounted, extends through the opening 2^a in the board, and the terminal wire connector 8^a is connected to the rear end of the stud by clamping nuts 9^a. The stud has a conical shoulder 3^a, which abuts against the front of the panel, and it is held in position in the panel by the nuts 9^a, which draw the shoulder against the panel. Surrounding the conical shoulder 3^a is an insulating washer 5^a, also conical, and a connecting plate 6^a also has a conical opening 6^a which, when the connector is placed upon the front of the board, as shown, receives the washer. The cap 7 is adjustable into and out of engagement with that portion of the connecting plate which surrounds the stud 3^a and connects and disconnects the stud and plate electrically. The plate is held in position by a stud 15, which passes through a

threaded opening 6^a in the plate and through an opening 2^b in the panel, and is provided with a clamping nut 16 at the front side of the panel, and with clamping nuts 11^a at the rear side of the panel, the latter also serving to secure the wire terminal 10^a to this stud. It will be evident without further description that the adjustment of the cap 7 will make or break the electrical connection between the terminals 8^a and 10^a. It will also be evident that these connections can be made or broken at the front of the board while the terminals themselves are at the rear.

In Figs. 5 and 6, the invention is shown in connection with conducting bars placed upon the same side of the panel as the cap which connects these bars. In these figures, upon the panel 1^b, two flat conducting bars 8^b and 10^b are shown, the bars having overlapping ends. The conductor 10^b is secured to the board by a threaded stud 17 which extends through the board, and a clamping nut 18 fitting on to said stud. The conductor 8^b is secured to the board by a threaded screw or stud 3^b, which passes through the board and has a threaded connection with said conductor, through which it also extends. The conductor and the stud are therefore electrically as well as mechanically connected together. The conductor 10^b has one end 10^c bent outward and overlapping the end of the conductor 8^b. This overlapping end of the conductor 10^b has an opening 10^d, through which the stud 3^b extends, and an insulated bushing 5^b fits within this opening and insulates the stud from the conductor 10^b. An insulating washer 5^b, which may be integral with or separate from the bushing 5^b, separates the overlapping ends 100 of the two conducting bars 8^b and 10^b. It will be evident that the adjustment of the cap 7 on the stud 3^b into and out of engagement with the conductor 10^b will make and break the electrical connections between the conductors 10^b and 8^b. While in this instance the conducting bars and the cap for making and breaking the connection between them, are shown on the front of the board, it will be evident also that, for some purposes, wire connections may be applied to the studs 3^b and 17 at the rear of the board, and that the operation of the cap 7 will make and break connections between such terminals.

What I claim is:

1. In an electric switch, a suitable base of insulating material, two terminals insulated from one another, one terminal having an opening therethrough and the other comprising a stud projecting from the base through said opening and having a threaded end extending beyond the first mentioned terminal, and a metal nut having an opening through which said stud extends when the

nut is at or near its closed position, said nut being adapted to make an annular contact with said first mentioned terminal.

2. In an electric switch, a threaded conducting stud, a conducting tube surrounding and insulated from the stud, said tube having an annular contact surface at one end, and said stud extending outwardly beyond said contact surface, and a connecting member, having a threaded opening therethrough, adjustable on the stud into and out of engagement with said surface.

3. In an electric switch, a threaded conducting stud, a conducting tube surrounding and insulated from the stud, said tube having a contact surface at one end which surrounds the stud, a connecting member, having a threaded opening therethrough, adjustable on the stud into and out of engagement with said surface and adapted to make an annular contact therewith, and attaching devices for conductors on said stud and tube, respectively.

4. A support of insulating material having an opening therethrough, and a switching device comprising concentric conducting members, insulated from one another and extending through said opening, the outer member having, at one side of the support, a contact surface which surrounds the inner member, and the inner member having, at the same side of the support, a threaded end, projecting beyond said contact surface, a connecting member, having a threaded opening therethrough, adjustable

on said threaded end, into and out of engagement with said surface and adapted to make an annular contact therewith, and means on each of said members, at the opposite side of the support, for attaching conductors thereto.

5. In an electric switch, a metal stud, threaded at one end, a metal tube surrounding and insulated from the stud and threaded at the corresponding end, a head fitting 45 the threaded end of the tube and surrounding the same, said stud projecting beyond said head, and a connecting member, having a threaded opening therethrough, threaded on to the stud and adapted to engage said head and make an annular contact therewith.

6. In an electric switch, a metal stud, threaded at both ends, a metal tube shorter than the stud and surrounding the same, 55 said tube being insulated from the stud and threaded at both ends, threaded means on corresponding ends of the stud and tube for connecting conductors thereto, and a threaded head and threaded connecting device at 60 the opposite ends of said tube and stud respectively, said connecting device adjustable into and out of engagement with said head.

In testimony whereof I have affixed my signature, in presence of two witnesses.

ROGER S. WHITE.
